(57) **CLAIM**

The ornamental design for an ear drops dispensing device as shown and described.

DESCRIPTION

FIG. 1 is a perspective view of an ear drops dispensing device showing my new design;

FIG. 2 is a front view thereof;

FIG. 3 is a rear view thereof;

FIG. 4 is a left side view thereof, the right side being a mirror image thereof;

FIG. 5 is a top view thereof; and,

FIG. 6 is a bottom view thereof;

The broken line(s) in the drawings illustrate portions of the ear drops dispensing device and form no part of the claimed design.

1 Claim, 6 Drawing Sheets
